UNITED STATES PATENT OFFICE.

ALFRED SPRINGER, OF CINCINNATI, OHIO.

TORSION-PIVOT BALANCE.

SPECIFICATION forming part of Letters Patent No. 340,013, dated April 13, 1886.

Application filed July 6, 1885. Serial No. 170,684. (No model.)

To all whom it may concern:

Be it known that I, ALFRED SPRINGER, a citizen of the United States, residing at Cincinnati, Ohio, have invented new and useful 5 Improvements in Torsion-Pivot Balances, of which the following is a specification.

My invention relates to torsion-pivot balances, its object being to produce a cheap and efficient balance for ordinary counter use.

10 To this end it consists in the balance hereinafter described, embodying the principles of the "torsion" pivot with its known and measurable resistance to deflection, arranged to indicate the degree of beam deflection upon 15 a graduated arc bar under load placed in the scale-pan.

Mechanism embodying my invention is illustrated in the accompanying drawings, in which Figure 1 is a perspective view of my improved 20 balance complete; Fig. 2 a vertical section of the same, to which is added a substitute form of indicating mechanism.

Referring now to the drawings, in which the parts described are indicated by letters of reference, it should be premised that it is immaterial whether the pivots are attached rigidly 25 to the beam and parallel bar or attached to separate frames, both modes of construction being heretofore described by me in Letters 30 Patent. In the illustration of my invention, I have selected the latter, in which illustration A designates the base, B the pedestal or beam-support, C the beam, and D the scale-pan, of 35 my improved balance. The pedestal or beam-support consists of a "torsion-frame," b, resting upon supports a, and provided with an 40 elastic wire or band, p, carried around the frame b and secured thereto in tension. The upper horizontal portion of the band p serves 45 as the fulcrum support of the beam C, and the lower horizontal portion as the fixed pivot of a rigid link or bar, C', arranged parallel with and below the beam. The outer ends of the beam C and of the link C' are connected at 50 equal distances from their pivots p p to the upper and lower portions, respectively, of a wire or band, p', stretched over a torsion-frame, b', similarly proportioned and constructed with the frame b, (omitting the mounting supports.) Upon the frame b' is mounted 55 the scale-pan D, upon supports d, the connec-

tion of the beam C and the link C' with the torsional pivots p p' thus being such as to preserve the scale-pan supports always in a vertical position. The beam C at its remote end 55 is provided with a weight, w, to counterbalance the scale-pan, for which purpose it may be adjustable, in order to accommodate an additional holding-vessel for an article to be weighed or for convenience in ascertaining net 60 weights.

In the drawings I have shown two arrangements of mechanism for actuating a pointer, either or both of which may be employed. The first of these consists of an indicating-finger, 65 E, suspended in a normally-vertical position from a pivotal support, g, attached to the beam-pedestal and actuated by contact of a curved finger, h, upon the beam. As the beam deflects under load upon the scale-pan it involves 70 a regularly-increasing torsional resistance of the pivots, the amount of deflection being in proportion to the load, and registered by the movement of the indicator E over the graduated arc plate I, from the initial point indicating the normal equilibrium. As this construction practically limits the graduated arc 75 to one-quarter of a circle, that shown at the right-hand of Fig. 2 may be substituted when a larger range of indication is desired. In the latter the beam C and link C' are extended a 80 convenient distance beyond the pivots p', and pivotally united by a ratchet-bar, k, engaging a spur-pinion carrying the indicator-finger F at the end of a suitably-mounted shaft. As the 85 mode of mounting is well understood, and would in this case obscure the drawings, I have not thought it necessary to show the details of the bearings. The indicator F is thus enabled to move over an entire circle one or more 90 times. The units of measure indicating the weight may thus be enlarged as desired.

I am aware that "spring-gravity" scales have long been known; but, owing to friction and the difficulty of securing uniformity and durability in the employment of ordinary springs, they have not been favorably regarded. The construction I have described, however, furnishes a means of distributing the load over a number of pivots, thus taxing each 95 in a very slight degree, far within the limit of perfect and durable action.

It will be obvious that any number of additional pivots may be brought into play by adding torsion-frames, similar to b' , (omitting the pan-supports d ,) between the beam C and link C'.

I claim as my invention and desire to secure by Letters Patent of the United States—

1. A torsion-balance embodying, in combination, a weight-lever fulcrumed upon an elastic fulcrum-pivot acting torsionally and a suitable indicator whereby the amount of beam-deflection against the torsional resistance of the pivot measures the weight applied to the beam, substantially as set forth.

2. The combination, in a gravity-balance, of a base, A, pedestal B, torsion-pivots p p' , terminal connection b' , a weight platform or support, an indicating-finger, and connecting mechanism for actuating the same over a graduated arc plate by the deflection of the beam, substantially as set forth.

In testimony whereof I have hereunto set my hand in the presence of two subscribing witnesses.

ALFRED SPRINGER.
